UNITED STATES PATENT OFFICE.

THOMAS E. BACUS, OF ADA, KANSAS.

SILO.

1,125,439.

Specification of Letters Patent.

Patented Jan. 19, 1915.

Application filed February 9, 1912. Serial No. 676,663.

To all whom it may concern:

Be it known that I, THOMAS E. BACUS, citizen of the United States, residing at Ada, in the county of Ottawa and State of Kansas, have invented certain new and useful Improvements in Silos, of which the following is a specification.

My invention relates to silos or like constructions, and has for its main object the provision of a relatively cheap, easily constructed, readily assembled and entirely effective construction of this character.

A further object is the provision in connection with a silo composed of staves, of means whereby the shrinkage of the staves may be taken up and particularly the provision in connection with a silo formed of staves, of a plurality of internal supporting rings or rims formed of sections and connected to each other so that the sections may be either expanded or contracted, so as to allow for any expansion or contraction of the staves laterally.

A further object is to provide in a silo an intermediate bracing ring or rim which is vertically shiftable so that it may be raised to the top of the silo in course of filling and so that as the contents of the silo are used, said intermediate rim may be lowered to protect the silo from collapse.

Other objects will appear in the course of the following description.

In the drawings: Figure 1 is a fragmentary plan view of the silo structure with the roof removed. Fig. 2 is a diametrical vertical section. Fig. 3 is a fragmentary elevation of the uppermost rim or bracing ring and a portion of a rafter, this figure showing the connection between the ring and the rafter. Fig. 4 is a fragmentary elevation of a portion of the rafter and the iron which connects the rafter to the rim, the rim being in section. Fig. 5 is a side elevation of the connecting members between the rim sections, the rim being in section. Fig. 6 is an end elevation of the device for connecting the sections of the wood rim together, the rim being in section. Fig. 7 is a sectional view of a modified form of connecting means. Fig. 8 is a fragmentary view of one of the staves forming the wall of the silo and a portion of the adjacent wood rim, and an elevation of one of the U-bolts holding the hoop to the staves and the staves to the wood rim.

Corresponding and like parts are referred

to in the following description and indicated in all the views of the drawing by the same reference characters.

In the preferred form of my construction, the body of the silo is composed of vertically disposed staves 2, although in many respects my invention is adapted to be applied to silos composed of artificial stone or concrete. The staves may extend longitudinally the whole of the length of the silo or may be constructed in sections spliced together as will be hereinafter described. The staves may be held in place by means of hoops 3 or in any other suitable manner, these hoops being preferably made in sections, the sections of the hoops being connected to each other by means of metal couplings.

Preferably the hoops are composed of three sections of five-eighths inch iron, the sections being connected together by couplings whereby the hoop may be contracted. As illustrated in Fig. 1, these couplings consist of blocks 4 having passages extending longitudinally therethrough, through which passages the ends of the hoop sections pass. The ends of the hoop sections are screw-threaded and nuts 4^a engage with these screw-threaded ends and thus permit the hoops to be contracted or expanded. I have found in practice that where the sections of the hoop are three in number the couplings should be capable of contracting the hoop 8 inches for each coupling, or 24" for the entire hoop.

The staves 2 are supported on any suitable base 5, which is shown as made of concrete. The interior of the silo is supported by means of a plurality of rims or rings 6, 7 and 8; the bracing rim 6 being shown at the top of the silo, the ring 8 at the bottom thereof, and the ring 7 being intermediate between the rings 6 and 8, and being vertically shiftable, as will be hereinafter described. Each of these rings is constructed in precisely the same manner, and hence a description of one will be applicable to all the rings 6, 7 and 8. These bracing rings are preferably composed of wood, each ring being made in a plurality of sections, shown as six in number, connected by expandible and contractible couplings. Preferably, there is a space of at least 2" between each of the sections 9 of the rim, as illustrated in Fig. 1.

Disposed upon the outer and inner faces

of the adjacent ends of the sections 9 of each rim are the longitudinally slotted, lateral plates or strips 10, these plates being preferably slotted from one end toward the other end. These plates are held in position at one end by a bolt passing through one of the rim sections or in any other suitable manner and held to the other rim sections by means of a bolt 11 passing through the slots of the plates.

The couplings I prefer to use for contracting and expanding the rim sections are preferably of the form shown in Figs. 5 and 7. Disposed upon one face of the rim sections 15 are the metallic brackets or brace blocks 12, each of the brackets being held to the adjacent rim sections by a bolt 13 provided with a nut 14. The extremities of the brackets 12 are perforated for the passage of a tightening bolt or screw 15. This tightening screw in the form illustrated in Fig. 6 is provided at one end with a head 16 and is also provided with the nuts 17 and 17^a disposed on each side of the adjacent bracket. By unscrewing one of the nuts and rotating the other nut, the brackets 12 will be drawn toward each other and will thus draw the sections of the wood rims together. By rotating the nuts in a reverse direction, it will be obvious that the brackets 12 and as a consequence the sections of the wood rim will be forced apart from each other. In the form shown in Fig. 7 the brackets 12 are connected by means of a screw rod 15^a provided with a head at its middle and having reversely disposed screw threads on each side of the head which screw threadedly engage the extremities of the brackets. By rotating this screw rod 15^a in one or the other direction, the wood rims may be drawn toward or forced away from each other.

After the silo has been put up and as the staves shrink, the brackets 12 are drawn toward each other, thus contracting the wood rims 6, 7 and 8, and thus permitting or accommodating shrinkage of the staves. At the same time, the hoops 3 are taken up by means of the couplings 4 so that the staves are forced into tight engagement with each other. This is done from time to time while the shrinkage of the staves lasts, and keeps the silo at all times tight and air proof.

While the bracing rims or rings 6, 7 and 8 are all of the same construction, the rim or ring 7 is vertically shiftable in the length of the silo and is not permanently disposed at the middle of the silo. The middle rim or ring 7 is normally adjusted to a less diameter than the body of the silo, and therefore 50 may be raised in the course of filling, and as the contents of the silo are used the said middle rim is lowered to protect the silo from collapse. When the rim reaches the middle of the silo, it may be permanently 65 expanded and held against any further

movement. Thus, when the entire silo is emptied, the silo is braced at its top, bottom and middle. This central rim 7 also protects the silo from collapse in cases where the silo is subjected to heat.

The wood rim 7 may be supported in any suitable manner but I have shown the rim supported by cords and counterweights, the rim being slightly heavier than the counterweight so that it will follow the ensilage 75 down as the ensilage is removed, the cords and counterweights permitting the wood rims to be very readily drawn up as the silo is filled.

The rim 7 is not connected to the silo, as 80 before explained, but the rims 6 and 8 are connected to the walls of the silo formed by the staves 2, by means of the U-shaped bolts or clips 18, illustrated in Fig. 8. These clips pass around the hoops 3, pass through the 85 staves forming the body of the silo, embrace the rims 6 or 8, and pass through the metal plate 19 disposed on the inner face of the rim. Nuts 20 operate on the ends of the U-shaped clips 18, and by tightening up 90 upon these nuts, the rim, staves and the outer hoops may be drawn into tight and rigid engagement. When it is desired to contract the silo walls in order to take up shrinkage, the nuts 20 are loosened, thus permitting a contraction of the hoop sections and also permitting a contraction of the rim embraced by the clips 18. Preferably, there is one of these clips 18 for each of the sections 9 composing the rim.

Where provision is made for the taking up of shrinkage of the wood staves forming the wall of the silo, provision must be also made whereby the wall of the silo may be contracted or expanded independently of the 105 roof. If the roof rafters are nailed to the staves or otherwise rigidly connected therewith, and shrinkage is taken up, either the staves are pushed out of position, or else the roof is buckled.

My invention contemplates the provision of means whereby while the roof is connected to the body of the silo, the body of the silo is yet independently contractible and expansible relative to the roof. For 115 this purpose, I provide a plurality of rafter anchor irons, designated 21, and illustrated in Figs. 1, 3 and 4. These anchor irons each consist of an angular shaped iron whose base is bolted to the section 9 of the rim 6, 120 and which is formed at one end of the base with the upwardly extending flange 22. This flange is triangular in face view so as to fit against the extremity of the adjacent roof rafter 23. The base of the anchor 21 is 125 longitudinally slotted as at 24. The anchor iron 21 is connected to the section 9 of the rim 6 by means of a bolt 26, which passes through the slot 24 and through a slot 27 in the rim 6. The bolt is preferably provided 130

with a head at one end, and carries at its other end a nut. By reason of the fact that the rim section is longitudinally slotted as at 27, the section 9 of the wood rim 6 may 5 be longitudinally shifted without affecting the position of the anchor iron.

The anchor iron is slotted parallel to the flange 22 to provide for an expansion or contraction of the rim 6, and also providing 10 for an expansion or contraction of the rafter 23. The slot 27 in the rim will allow the wood forming the rim section to expand or contract without disturbing the roof, while the slot 24 will allow the rim or plate 21 to 15 move inward or outward without disturbing the roof. By this construction the shrinkage of the staves may be taken up without affecting the roof or the staves, and without causing the staves to be pushed out 20 of place or the roof to be buckled. It will be seen that by reason of the roof being attached to the upper rim or ring 6 by bolts, the roof may be taken off at any time without damage. The staves extend up beyond 25 the upper rim about an inch except at the intersection of a rafter where the end of the stave is cut off flush with the inner face of the rim to permit the projection of the rafter.

30 Disposed upon the rafters in any suitable manner is the roofing 28, which may be of any suitable material, but is preferably composed of rubberoid roofing. This rubberoid roofing extends beyond the outer face of the 35 wall of the silo, as illustrated in Fig. 2.

It will be seen that I have provided with this construction a means whereby the roof may be operatively connected to the body of the silo, which will, however, permit a 40 taking up of shrinkage in the staves forming the body of the silo without affecting the roof, and which will permit the roof to be removed or replaced at any time without trouble. It will also be seen that I have 45 provided a very strong and substantial anchorage between the roof and the silo body, and have provided connecting devices, which, while rigidly connecting the bracing rims, permit the sections of each rim to be 50 drawn toward each other or forced apart from each other for contracting or expanding said rims.

As before stated, certain details of my construction may be used with a silo not 55 constructed of vertically disposed staves,

and might, indeed, be used even with a silo constructed of concrete or brick. For instance, I do not wish to be limited to the use of the interior bracing rings 6, 7 and 8, with a silo composed of vertical staves, 60 although these bracing rings, particularly the rings 6 and 8, are particularly adapted to be used with such construction because they permit the expansion and contraction of the silo wall. The bracing ring 7 which 65 moves vertically from the upper end of the silo to the middle thereof, or below the middle, if desired, is capable of use with a concrete or brick silo, as it will perform its function of bracing the silo wall in either 70 case.

Having thus described my invention, what is claimed is:—

1. In a silo, a horizontally disposed internal annular brace bearing against the 75 silo walls and disconnected therefrom, said brace being vertically shiftable the entire length of the silo, said brace being contractible and expansible.

2. A silo, having annular interior braces 80 at its upper and lower ends and an intermediate annular brace expansible against the inner wall of the silo, and vertically shiftable the entire length thereof.

3. A silo having upper and lower sec- 85 tional annular bracing rims bearing against the interior face of the silo, an intermediate annular sectional bracing rim also bearing against the inner face of the silo, and expansible and contractible means connecting 90 said sections of the bracing rims, said intermediate rim being disconnected from the silo wall and being vertically shiftable the entire length of the silo.

4. A silo having an interior annular 95 bracing rim bearing against the interior face of the silo wall and vertically shiftable therein the entire length of the silo, said rim being composed of spaced sections, brackets having outstanding lugs mounted upon the 100 faces of the sections, and screw rods for the brackets whereby the brackets may be drawn apart or forced together to expand or contract the rim.

In testimony whereof, I affix my signature 105 in presence of two witnesses.

THOMAS E. BACUS. [L.S.]
